DESIGN FOR A GOBLET OR SIMILAR ARTICLE

Edgar M. Bottome, Moundsville, W. Va., assignor
to Fostoria Glass Company, Moundsville, W.
Va., a corporation of West Virginia

Application April 14, 1938, Serial No. 76,490

Term of patent 3½ years

To all whom it may concern:

Be it known that I, Edgar M. Bottome, a citizen of the United States of America, and resident of Moundsville, county of Marshall, and State of West Virginia, have invented a new, original, and ornamental Design for a Goblet or Similar Article, of which the following is a specification, reference being had to the accompanying drawing, forming part thereof, in which—

The single figure is a side elevation of a goblet

of conventional contour, showing my new design. In said figure the outline of the goblet is depicted by dotted lines.

The surface ornamentation is repeated throughout the entire peripheral extent of the goblet.

I claim—

The ornamental design for a goblet or similar article, substantially as shown and described.

EDGAR M. BOTTOME.
